(57) **CLAIM**

The ornamental design for a nonwoven web product with surface indicia, as shown and described.

DESCRIPTION

The Sole FIGURE is a top plan view of an embodiment of a nonwoven web product with surface indicia showing my new ornamental design it being understood that the outer perimeter of broken lines indicates that a specific length and width of the nonwoven web product with surface indicia forms no part of the claimed design.

The broken line showings are for illustrative purposes only and form no part of the claimed design. The broken lines shown along the border of the figures indicate that the design may continue indeterminately in one or more directions. The broken lines shown along the border form no part of the claimed design.

The surfaces or portions not shown in the drawings or described in the specification form no part of the claimed design.
